Des. 237,757
Patented Nov. 25, 1975

237,757

GOGGLE EYEPIECE

Lloyd S. Turner, Los Gatos, Calif., assignor to Hind-Wells, Inc., San Luis Obispo, Calif.

Filed May 23, 1974, Ser. No. 472,729

Term of patent 14 years

Int. Cl. D2—03

U.S. Cl. D2—234

FIG. 1.

FIG. 3.

FIG. 5.

FIG. 2.

FIG. 6.

FIG. 4.

FIG. 7.

FIG. 1 is a view in perspective of a goggle eyepiece showing my new design;

FIG. 2 is a top plan view of the eyepiece of FIG. 1;

FIG. 3 is a view in rear elevation of the eyepiece;

FIG. 4 is a view in front elevation of the eyepiece;

FIG. 5 is a view taken along lines 5—5 of FIG. 2;

FIG. 6 is a view taken along lines 6—6 of FIG. 2; and

FIG. 7 is a view in section taken along lines 7—7 of FIG. 4.

I claim:

The ornamental design for a goggle eyepiece, as shown.
